(57) **CLAIM**

The ornamental design for a LED lantern, as shown and described.

DESCRIPTION

FIG. 1 is a perspective view of a LED lantern showing my new design;

FIG. 2 is another perspective view thereof;

FIG. 3 is a front elevational view thereof, the rear elevational view being a mirror image of FIG. 3 and therefore not shown;

FIG. 4 is a left elevational view thereof, the right side view is identical and therefore not shown;

FIG. 5 is a top plan view thereof;

FIG. 6 is a bottom plan view thereof;

FIG. 7 is a perspective view of the LED lantern shown separated for clarity of disclosure; and,

FIG. 8 is another perspective view thereof.

The broken lines in the drawings depict portions of the LED lantern that form no part of the claimed design.
